APPARATUS FOR WORKING METAL

Karl B. Kaiser, Rockford, Ill., assignor to The Ingersoll Milling Machine Company, Rockford, Ill., a corporation of Illinois

Application August 17, 1951, Serial No. 242,261

8 Claims. (Cl. 80—14)

1

This invention relates to apparatus for working the metal of elongated bars such as tubes to reduce the cross section thereof and correspondingly lengthen the bars.

Heretofore, such rolling out of the metal of the bars has been effected by cams or rolls having vacant sectors which when disposed opposite the tube or bar permit periodic endwise feeding by which a new length of bar is presented to the rolls. In the so-called pilger mill, the rolls are journaled on a stationary frame which is advantageous in view of the rugged mounting required but disadvantageous in that the rolls are idle for half of each revolution during which the bar is fed forwardly. In the so-called tube reducing process, greater production is achieved by mounting the rolls on a carriage which is reciprocated back and forth along the stationary work bar so that the rolls may work the metal in both of their oscillating movements. This method requires a costly machine structure for guiding the roll carriage, necessitates reciprocation of a heavy mass, and complicates the procedure of changing the rolls.

The primary object of the present invention is to provide a bar reducing apparatus which combines all of the advantages and overcomes the disadvantages of the two methods above referred to.

Another object is to provide a novel mechanism for reciprocating the work bar, oscillating the rolls, and intermittently feeding the work in synchronism while permitting the rolls to be mounted in a stationary frame.

A more detailed object is to reciprocate the work back and forth and at the same time to utilize the work reciprocations as a source of power for oscillating the working rolls back and forth.

The invention also aims to achieve the foregoing object through the mounting of the intermittent work feeding mechanism on the reciprocating work carriage.

Other objects and advantages of the invention will become apparent from the following detailed description taken in connection with the accompanying drawings, in which

Figure 1 is a fragmentary side elevational view of a metal working machine embodying the novel features of the present invention.

Fig. 2 is a fragmentary sectional view taken along the line 2—2 of Fig. 1.

Fig. 3 is a fragmentary cross section through the rolling dies and the workpiece.

Figs. 5, 6 and 7 are fragmentary cross sec-

2

tional views taken respectively along the lines 5—5, 6—6 and 7—7 of Fig. 4.

Figs. 8, 9 and 10 are fragmentary cross-sectional views taken along the lines 8—8, 9—9 and 10—10 of Fig. 1.

Fig. 11 is a fragmentary longitudinal sectional view taken along the line 11—11 of Fig. 9.

Fig. 12 is a sectional view taken along the line 12—12 of Fig. 11.

10 Figs. 13 and 14 are schematic plan views showing the parts at the right and left hand ends of the machine shown in Fig. 1.

Figs. 15 through 18 are schematic views illustrating the action of the work feeding mechanism.

Fig. 19 is a fragmentary sectional view taken along the line 19—19 of Fig. 9.

Fig. 20 is a fragmentary section taken along the line 20—20 of Fig. 6.

20 While the invention is susceptible of various modifications and alternative constructions, I have shown in the drawings and will herein describe in detail the preferred embodiment. It is to be understood, however, that I do not intend to limit the invention by such disclosure, but aim to cover all modifications and alternative constructions falling within the spirit and scope of the invention as expressed in the appended claims.

30 The invention is shown for purposes of illustration incorporated in a machine for reducing the diameter, both inside and outside, of a metal tube 10 by the cold forging action thereon of semicircular rolls 11 journaled in a stationary frame 12 at one end of a bed 13 which carries the power driven mechanisms for reciprocating the work tube, periodically feeding the same endwise in short increments, turning the tube step by step, and oscillating the rolls 11.

40 In general, the trailing end portion of the tube is fastened through a gripper 15 and an intermittently acting feed mechanism 16 (Fig. 4) to a carriage 17 slidable back and forth along the bed to reciprocate the work tube and correspondingly oscillate the rolls 11 back and forth between the limit positions shown in Figs. 15 and 16. After the active roll surfaces have passed out of engagement with the work at the end of the retraction of the latter, the feed mechanism

45 is actuated to advance the work a short distance relative to the carriage to present a new portion of the tube to the rolls. Also, at each end of the carriage stroke, the tube is turned through a partial revolution to present any flash formed at the junction of the two roll surfaces to be rolled away in the next stroke.

50 A mandrel 18 disposed within the tube between

the rolls 11 projects outwardly through the trailing end of the tube 10 where it is detachably fastened to the carriage 17 and held against axial movement relative thereto. Where it is desired to reduce the internal as well as the external work diameter, the mandrel is tapered as indicated at 19 (Fig. 3).

The rolls 11 are grooved as shown in Fig. 10 to straddle opposite halves of the work tube and each axial section has a gradual cam rise 20 extending over somewhat more than a half revolution so as to leave a vacant sector on one side of the roll permitting endwise advance of the work tube when the rolls are positioned as shown in Figs. 15 and 18. The rolls are fast on suitable shafts 21 journaled in bearings supported in the side walls of the frame 12. Preferably, each roll is backed by a roll 22 also supported in the frame 12.

The carriage 17 by which the work is reciprocated back and forth is slidably in heavy guides 23 (Fig. 2) formed along opposite sides and on the top of the bed 13. Power for reciprocating the slide is derived from a motor 24 (Fig. 13) mounted in the bed and, through speed reduction gears 25, drives two gears 26 which carry crank pins 27 joined by connecting rods 28 to an oscillating arm 29 pivoted at 30 (Fig. 1) on the bed 13. The latter is of substantial width and at its free end is formed with spur teeth 30 meshing with the teeth of a rack 31 secured to the under side of the carriage 17. During operation of the motor, the gear segment 29 is rocked back and forth and the carriage moved correspondingly along the ways 23.

In accordance with one aspect of the present invention, the reciprocatory motion of the carriage 17 is utilized directly to oscillate the rolls 11 in opposite directions in accurate synchronism with the back and forth movements of the work tube 10. Herein, the motion converting mechanism includes a link 32 (see Fig. 14) pivoted at 33 on the forward end of the carriage 17 and pivotally connected at 34 to one end of a rack bar 35 which is slidable in guides 36 formed on the base part of the roll frame 12 (Fig. 10). A pinion 37 journaled on the frame 12 meshes with the teeth of the rack 35 and also with a gear 38 fast on the lower roll shaft 21. Another gear 38^a on the shaft 21 meshes with a gear 39 on the shaft of the upper roll. As a result, the rolls turn in the direction indicated by the arrows in Fig. 14 while the carriage 17 is advancing to the left and in the reverse direction while the carriage is moving in the opposite direction.

Mounted on the carriage 17 and movable relative thereto in guideways 41 formed thereon parallel to the ways 23 is a slide 40 on which the tube gripper 15 is journaled. The ways 41 are long enough to permit movement of the slide through a range somewhat greater than the length of the tubes 10 to be operated on. The trailing tube end (see Figs. 6 and 20) is received in a ring 42 having angularly spaced inwardly opening recesses 43 receiving jaws 44 which abut against the tube end. The coned external surfaces of the jaws fit into complementary surfaces 45 on a ring 46. Through thrust washers 47, the latter ring abuts against an inturned flange 48 on a collar 49 screw threaded at 50 onto a nut 51 threaded onto the end of a tube 52 having spur teeth 53 formed thereon. By applying a spanner wrench to holes 54, the collar 49 may be turned relative to the nut 51 and moved axially causing the internally coned ring 46 to collapse the jaws 44 around the work 75 mounted on the bed 13 and the frame 58, this

tube or allow expansion of the jaws to release the tube. The tube 52 is journaled in bearings 55 at opposite ends of a hole 56 extending through a slide 40 concentric with the tube.

5 A second device 57 (Figs. 1, 8 and 14) is adapted to grip the reduced end portion of the work tube 10 beyond the rolls 11 and apply a torque for assisting the gripper 15 in turning the tube while permitting the tube to slide endwise therethrough 10 as it is elongated in the rolling operation. This auxiliary gripper is mounted on a frame 58 and includes a slide 60 (Fig. 8) guided along ways 59 and connected to the forward end of the carriage 17 by links 61 disposed along opposite sides of the roll frame 12.

Extending through and journaled in an elongated bearing 60^a in the slide 60 is a sleeve 62 held against axial movement by thrust washers 63. A ring 64 surrounding the sleeve 62 and sliding along a key 65 thereon is urged axially by springs 66 which act against a nut 67 threaded onto the sleeve to adjust the spring tension.

The outer end of the ring 64 bears against the free ends of angularly spaced radially disposed arms 68 pivoted at their inner ends on pins 69 carried by the sleeve 62. Outward swinging of the arms 68 is limited by adjustable stops 70 on the slide 60. Swingable on pivot pins 71 on the arms 68 and projecting inwardly therefrom are angularly spaced jaws 72 whose inner ends project through holes 73 in the sleeve 62 and bear against the exterior of the work tube 10, the reduced end portion of which extends axially through the sleeve. The pins 71 are radially spaced outwardly slightly beyond the pins 69. It will be seen that the jaws 72 are always urged into frictional gripping engagement with the tube 10 by the action of the springs 66 on the arms 68 and are thus adapted at all times to transmit 40 rotary torque to the tube 10. At the same time, however, and by virtue of the relative radial spacing of the pivots 69 and 71, the jaws 72 and the arms 68 on which the latter are carried are yieldable outward by rocking of the arms 68 away from the stop 70 and against the action of the springs 66. This permits endwise shifting of the engaged part of the tube 10 through the sleeve 62. Such shifting occurs during the step by step forward feeding of the tube and also as a result of 50 the elongation of the tube which accompanies the reducing action of the rolls 11. The forward end portion of the sleeve 62 is fluted as indicated at 75 and spline coupled to a gear 76 journaled in bearings 77 in a part 78 which is bolted to the top of the frame 58 beyond the range of reciprocation of the gripper 57.

A turning moment derived from the motor 24 is applied periodically to the grippers 15 and 57 to rotate the tube 10 through part of a revolution, usually about $\frac{1}{4}$ of a revolution, while the surfaces of the rolls 11 are out of engagement with the tube end of each stroke of the carriage 17. For this purpose, a shaft 79 (Figs. 1, 13 and 14) carrying the carriage drive gears 25 is connected by bevel gears 80 to a horizontal shaft 81 journaled on the bed 13. The shaft 81 (Fig. 14) is bevel geared to a shaft 82 carrying a cam 83 which acts on a follower 84 to swing an arm 85 about a pivot 86 a distance determined by the 65 rise of the cam. The rocking motion of the arm 85 is imparted to the driving pin 86^a of a ratchet or other type of one-way clutch 87 by which a gear 88 is correspondingly turned. Through a suitable gear connection 89 and a shaft 89^a mounted on the bed 13 and the frame 58, this

motion is transmitted in the proper direction to the gear 76 by which the gripper 57 is turned. The cam shaft 82 makes one revolution during each forward and return stroke of the carriage 17 and the cam 83 is shaped to advance the shaft 90 one step while the rolls 11 are out of engagement with the tube 10 at the end of each carriage stroke.

In a similar way, the motion is applied in the proper direction to a shaft 90 (Figs. 13 and 14) journaled on the bed 13 and spline coupled to a gear 91 meshing with the gear 53 by which the gripper 15 is driven. The shaft 90 is extended further along the bed and, at its rear end (Fig. 13), is splined into a gear 92 journaled on the bed 13 and meshing with spur teeth on the exterior of a ring 93 (Figs. 11 and 13). The latter is journaled in bearings 94 on an extension 99 of the carriage 17 and held against axial movement by thrust washers 95. The ring gear is formed with internal teeth 96 meshing with teeth on the exterior of a drive ring 97 slidably keyed at 98 onto the longitudinally grooved rear end portion 18^b of the mandrel 18.

Means is provided for holding the mandrel solidly against endwise movement relative to the carriage 17 during the tube reducing operation while permitting step by step turning of the mandrel and also endwise withdrawal of the latter preparatory to inserting a new work tube. Herein, this means includes a spool 100 (Fig. 11) journaled on a sleeve 101 and clamped by a nut 102 between thrust members 103. The sleeve in turn is clamped between nuts 104 threaded onto reduced portions of the mandrel.

Projectable into and out of the groove of the spool 100 are plungers 105 (Figs. 9 and 11) guided in ways on the carriage extension 99 and shaped at their inner ends to fit closely around the spool. Rack teeth on the outer ends of the plungers mesh with gear segments 106 pivoted at 107 on the extension 99. The free ends of the segments are pivotally connected at 108 to a link 109 which is joined to a rod 110 slidable vertically in the extension 99. The rod carries a piston 111 movable in a stationary cylinder 112. By admitting pressure fluid to the upper and lower ends of the cylinder, thrust sustaining plungers may be moved out of and into the groove of the spool 100 to lock or release the mandrel. When the plungers are withdrawn, the mandrel with the spool and the ring 97 thereon may be withdrawn rearwardly through the hollow ring gear 93.

If desired, such withdrawal may be effected by a power actuator of the type shown in Figs. 11 and 12 and including a non-circular tube 113 surrounding the rear end portion 18^b of the mandrel and clamped by a nut 114 against the ring 97. Teeth 115 formed along the upper side of the tube are adapted to receive between them the tapered end 116 of a plunger 117 normally urged into the locking position shown in Fig. 11 but withdrawable by energization of a solenoid 118. The plunger is slidable in an extension 119 on a slide 120 which loosely surrounds and guides the tube 113 and itself is guided in ways 121 on another extension 122 of the machine bed 13. A lug 123 on the underside of the slide 120 is coupled to an endless chain 124 extending around sprockets 125 one of which is on a shaft 129 adapted to be turned through a slip clutch connection 126 with a gear 127. The latter may be rotated by hand or, as shown diagrammatically in Fig. 12, by a reversible electric motor actuator 128.

When the actuator is energized in one direc-

tion after release of the thrust plungers 105, the slide 120 with the mandrel 18, the ring 97, and the spool 100 coupled thereto are drawn rearwardly along the bed ways 121 far enough to permit a new tube 10 to be inserted endwise into the gripper 15 between the latter and the trailing end of the previous tube then disposed between the rolls 11. In the reverse or forward movement of the mandrel slide, the mandrel is advanced through the new tube until an adjustable screw 130^a (Fig. 11) on the ring 97 comes against the end of the gear 93. At that time, the clutch 126 will slip and the tapered end of the mandrel will be located correctly in relation to the rolls 11.

The mechanism 16 above referred to operates to feed the tube 10 forwardly intermittently in timed relation to the reciprocations of the carriage 17 and irrespective of the position of the slide 40 along the carriage. To operate reliably under the heavy forces involved, this mechanism is of rugged construction and adapted to act positively. It comprises generally screws 130 (Figs. 4 to 7) mounted on the carriage 17 and rotating continuously to advance the slide 40 in one direction relative to the carriage and a cam device 131 (Figs. 4 to 13) mounted on the slide and rotated continuously to advance the gripper 15 relative to the slide in the opposite direction so as to neutralize the screw motion during the time that the work is engaged by the rolls 11 while advancing the gripper 15 to feed the tube when the rolls are out of engagement with the tube at the end of the forward stroke of the carriage 17.

Referring to Figs. 4 to 7 and 15 to 19, the screw 130 is duplicated on opposite sides of the slide 40 and threads through nuts 132 secured in opposite ends of bores 133 through which the screws extend parallel to the axis of the work tube. The screws are somewhat longer than the lengths of the work tubes 10 and at their rear ends are journaled in bearings 134 (Fig. 19) on the carriage 17 and firmly held against endwise movement by heavy thrust washers 135. Fast on the rear ends of the screws are worm wheels 136 meshing with worms 137 (Fig. 13) on a cross-shaft 138 journaled on the carriage and connected through interchangeable pick-off gears 139 with a shaft 140. A train of bevel and spur gears 141 rotatably mounted on the carriage 17 extends from the shaft 140 to a gear 142 splined on a shaft 143 journaled on the bed 13 and connected through a worm and worm wheel 144 to a drive shaft 145. This shaft may be driven by an electric rapid return motor 146 or from the main motor driven shaft 81 through bevel gears 147 and a one tooth clutch 148 having jaws which interengage in only one angular position of the driving and driven parts which may be engaged and disengaged by axially shifting the clutch collar 149 by any suitable means (not shown).

The screws and their drive connections are so constructed that in each stroke d of the carriage 17, the slide will be advanced relative to the carriage a distance a (Fig. 15). In a complete cycle or during both forward and return strokes of the carriage, the slide is advanced a distance b (Fig. 16).

In the present instance, the positively acting cam device 131 comprises two open face cams 150 (Figs. 4 and 13) disposed on opposite sides of and acting against rollers 151 on a follower lever 152 fulcrumed intermediate its ends on a pin 153 on a casing 154 secured to the top of the slide. The cams 150 which rotate in planes paralleling the work axis are keyed to shafts 155 journaled

in the casing 154 and carrying gears 156 which are joined by bevel gears 157 to a spline shaft 158. This shaft projects rearwardly from the slide 40 and at its end is adapted to be coupled by a one tooth clutch 159 to a gear 160 which is driven through suitable gearing 161 from the shaft 143. The clutch may be engaged and disengaged by a hydraulic actuator 162.

The other or inner end of the lever 152 is forked as shown in Figs. 6 and 7 to straddle a collar 163 having trunnions 164 thereon projecting through holes in the lever. The collar is disposed between thrust washer abutments 165 on a sleeve 166 keyed to but slidable along the sleeve 52 above referred to. Heavy coiled springs 167 acting in compression between abutments on the sleeves 52 and 166 serve as slightly yieldable cushions between the cams and the gripper 15 actuated thereby.

The cam shafts 155 are timed to make one complete revolution during one cycle of reciprocation of the carriage 17. At the end of the forward stroke of the carriage and after the work tube 10 has been fed forwardly by the cams 150, the parts will be positioned as shown in Figs. 4 and 15, one follower roller 151 engaging the high point of the forward cam 150 and the low point of the other cam. Now, during retraction of the carriage 17 and the work tube to the position shown in Fig. 16, the screws 130 move the slide progressively and forwardly relative to the carriage 17 a distance a and at the same time the cams 150 turn clockwise through a half revolution rocking the follower lever 152 progressively to the perpendicular position shown in Fig. 16 thus retracting the gripper 15 relative to the slide 40 an amount indicated at b and equal to the distance a , the parts then being positioned as indicated in Fig. 16.

Advance of the slide 40 by the screws continues in the next or forward stroke of the carriage 17 by a distance e during which the counterclockwise rocking of the follower lever 152 is continued by the gradual rise of the forward cam 150 and a corresponding fall in the rear cam. The gripper 15 is thus further retracted relative to the slide a distance f equal to the distance e . The parts are then positioned as shown in Fig. 17, the rollers 11 having passed out of engagement with the work tube 10. The sharp rise 170 (Fig. 4) of the forward cam and the corresponding fall 171 of the other cam are then presented to the follower rollers 151 in the final part of the cam revolutions thus shifting the lever 152 quickly in the reverse or clockwise direction from the position shown in Fig. 17 to that of Fig. 18. The gripper 15 is thus projected forwardly relative to the slide 40 a distance g , and the work tube is fed forwardly through the rolls 11 to bring a new length h of the unreduced tube into operative association with the rolls. The cycle of reciprocation of the carriage is now complete, and the parts are again in the starting position above assumed.

Operation

The operation of the machine as above described may be summarized with reference to Figs. 15 to 17 assuming that the carriage 17 is fully advanced and the work tube has been fed forwardly as shown in Fig. 15. As the carriage moves backwardly and to the right, the rolls 11 turn in the direction indicated in Fig. 15 into engagement with the work at the unreduced di-

ameter thereof and, in the continued movement, roll out the metal progressively to the reduced diameter. This results in an elongation of the leading end portion of the tube beyond the rolls which is permitted by the one way action of the gripper 15 as described above.

At the end of the backward stroke of the carriage, the rolls will have passed out of engagement with the tube as shown in Fig. 16. Thereupon, the cam 83 acts through the one way clutch 87 to turn the shaft 90 through one step and thereby apply to both of the tube grippers 15 and 57 and to the mandrel 18 a torque for turning the same usually through about one seventh of a revolution.

Now, as the carriage 17 and the work tube are pushed in the next stroke, the rolls 11 are turned reversely as indicated in Fig. 16 and engage the tapered portion of the tube progressively to further roll out the metal of the tapered part of the tube. As the carriage reaches its forward limit of travel (Fig. 17), the rolls pass out of engagement with the tube and the cam 83 again operates to turn the tube grippers 15 and 57 and the mandrel 18. At the same time, the cams 159 operate as described above to feed the gripper 15 and the tube forwardly through the distance g (Fig. 18) thus presenting a new length of the tube to the rolls and completing the machine cycle.

Successive cycles are repeated until the trailing end of the tube has reached a predetermined position at which the machine is stopped preparatory to inserting a new tube. To accomplish this, the gripper 15 is released manually, both of the one tooth clutches 149 and 159 are disengaged, and the motor 128 is started in a direction to retract the mandrel 18 out of the tube 10 a distance somewhat greater than the length of the new tube to be inserted. Next, the rapid traverse motor 146 is started in a direction to cause the screws 130 to retract the slide 40 and the gripper 15 relative to the carriage 17 a distance sufficient to enable the new tube to be inserted in the latter which is then tightened. The motor 146 may be operated reversely until the leading end of the new tube comes into abutment with the end of the partially reduced tube.

By operating the motor 128 reversely, the mandrel 18 is next moved axially through the new tube and until a stop 130^a (Fig. 11) on the ring 97 moves with the mandrel slide 113 and encounters the end of the gear 93. The tapered end of the mandrel will then be positioned accurately in the proper position between the rolls 11.

After reengagement of the clutches 149 and 159, the machine may be restarted. In the ensuing cycles of the machine, the leading tube is urged backwardly by the action of the rolls 11 and thus is always held in proper abutment with the leading end of the new tube.

I claim as my invention:

1. In a bar reducing machine, the combination of, a stationary frame, a carriage guided for reciprocation on said frame, means on said carriage for fastening one end portion of a work bar thereto for movement back and forth with the carriage, forging rolls journaled on said stationary frame to receive the other end portion of the supported bar, power operated means for reciprocating said carriage back and forth, a rack bar connected to said carriage and projecting past said rolls, gearing interconnecting said rolls and the teeth of said rack bar and operable to os-

cillate said rolls in opposite directions and back and forth during reciprocation of said carriage, mechanism mounted on said carriage for movement therewith for holding the work bar positively against endwise movement and operable when actuated to positively feed the work bar forwardly relative to the carriage, and means connecting said power operated means and said mechanism and operable while said carriage is disposed near the end of its forward stroke to transmit a positively measured increment of movement of said power operated means to said feed mechanism.

2. In a bar reducing machine, the combination of, a stationary frame, a carriage guided for reciprocation on said frame, means on said carriage for fastening one end portion of a work bar thereto for movement back and forth with the carriage, forging rolls journaled on said stationary frame to receive the other end portion of the supported bar, a power rotated drive shaft, means driven by said shaft to reciprocate said carriage back and forth, a rack connected to said carriage and reciprocating therewith, gearing on said frame interconnecting said rolls and the teeth of said rack and operable to oscillate said rolls in opposite directions and back and forth during reciprocation of said carriage, mechanism including a rotary member mounted on said carriage and operable by its rotation to feed the work bar forwardly relative to the carriage, a shaft spline coupled to said rotary member and extending along said carriage, and means driven from said drive shaft and operable to turn the spline shaft one step while said carriage is disposed at each end of its range of reciprocation.

3. In a bar reducing machine, the combination of, a stationary frame, a carriage guided for reciprocation on said frame, a gripper rotatably mounted on said carriage for fastening one end portion of a work bar thereto for movement back and forth with the carriage, forging rolls journaled on said stationary frame to receive the other end portion of the supported bar, a power rotated drive shaft, means operated thereby to reciprocate said carriage back and forth, gearing interconnecting said rolls and said carriage and operable to oscillate said rolls in opposite directions and back and forth during reciprocation of said carriage, mechanism mounted on said carriage and operable to feed said gripper forwardly relative to the carriage while the latter is disposed at the end of its forward stroke, a second gripper movable with said carriage and engageable with the reduced end portion of the work bar beyond said rolls, said second gripper having jaws movable to permit of endwise elongation of said bar by said rolls, and means driven by said drive shaft and actuated intermittently and at the end of a stroke of said carriage to turn both of said grippers.

4. In a bar reducing machine, the combination of, a stationary frame, a carriage reciprocable back and forth in ways supported by said frame, a slide mounted on said carriage for reciprocation relative thereto parallel to said ways, a gripper for clamping the trailing end of a work bar and mounted on said slide for movement relative thereto parallel to said ways, metal working rolls journaled on said frame to receive and operate on the forward end portion of a bar clamped in said gripper, a power rotated drive shaft, means driven from said shaft for reciprocating said carriage, means for converting the reciprocatory motion of said carriage into oscillatory motion

of said rolls, a screw threading into said slide along the path of reciprocation thereof and rotatably mounted on said carriage, means driven from said shaft and turning said screw continuously to advance said slide relative to said carriage, a lever fulcrumed on said slide and connected to said gripper to shift the same back and forth parallel to said ways, and cam mechanism rotated in synchronism with said screw and operable through said lever to positively retract the gripper relative to said slide during the return and forward strokes of said carriage and advance the gripper while the carriage is at the end of its forward stroke, the rate of retraction of said gripper by said cam mechanism being equal to the rate of advance of said slide by said screw.

5. In a bar reducing machine, the combination of, a stationary frame, a carriage reciprocable back and forth in ways supported by said frame, a slide mounted on said carriage for reciprocation relative thereto parallel to said ways and through a range greater than the length of a work bar to be reduced, a gripper for clamping the trailing end of a work bar and mounted on said slide for movement relative thereto parallel to said ways, metal working rolls journaled on said frame to receive and operate on the forward end portion of a bar clamped in said gripper, a power rotated drive shaft, means driven from said shaft for reciprocating said carriage, means for converting the reciprocatory motion of said carriage into oscillatory motion of said rolls, a screw threading into said slide along the path of reciprocation thereof and rotatably mounted on said carriage, means driven from said shaft and turning said screw continuously to advance said slide relative to said carriage, a rotary cam mechanism mounted on said slide and driven continuously from said drive shaft, and a follower positively actuated by said cam mechanism operable to advance and retract said gripper relative to the slide, said cam mechanism being shaped to retract said gripper progressively relative to the slide during the retraction and advance of said carriage at the rate of advance of said slide by said screw and at the end of the carriage advance to feed said gripper forwardly relative to the slide.

6. In a bar reducing machine, the combination of, a stationary frame, a carriage reciprocable back and forth in ways supported by said frame, a slide mounted on said carriage for reciprocation relative thereto parallel to said ways, a gripper for clamping the trailing end of a work bar and mounted on said slide for movement relative thereto parallel to said ways, metal working rolls journaled on said frame to receive and operate on the forward end portion of a bar clamped in said gripper, a power rotated drive shaft, means driven from said shaft for reciprocating said carriage, means for converting the reciprocatory motion of said carriage into oscillatory motion of said rolls, means driven from said shaft and operable continuously to advance said slide relative to said carriage, and a rotary cam mechanism driven continuously from said drive shaft and operable to retract said gripper progressively relative to the slide during the retraction and advance of said carriage and, at the end of the carriage advance, to feed said gripper forwardly relative to the slide, the rate of retraction of said gripper by said cam mechanism being equal to the rate of advance of said slide by said last mentioned means.

7. In a bar reducing machine, the combina-

tion of, a stationary frame, a carriage reciprocable back and forth in ways supported by said frame, a slide mounted on said carriage for reciprocation relative thereto parallel to said ways and through a range greater than the length of a work bar to be reduced, a gripper for clamping the trailing end of a work bar and mounted on said slide for movement relative thereto parallel to said ways, metal working rolls journaled on said frame to receive and operate on the forward end portion of a bar clamped in said gripper, a power rotated drive shaft, means driven from said shaft for reciprocating said carriage, means for converting the reciprocatory motion of said carriage into oscillatory motion of said rolls, screw and nut elements mounted on said carriage and continuously driven from said shaft to advance said slide relative to said carriage, and cam and follower elements on said carriage driven continuously from said drive shaft and operable to advance and retract said gripper relative to said carriage during the retraction and advance thereof and at the end of the carriage advance to feed said gripper forwardly relative to the carriage, the rate of advance of said gripper being equal to the rate of advance of said slide by said screw.

8. In a bar reducing machine, the combination of, a stationary frame, a carriage guided for reciprocation on said frame, means on said carriage for fastening one end portion of a work bar thereto for movement back and forth with the carriage, forging rolls journaled on said stationary frame to receive and work the other end

portion of the supported bar, a power driven shaft, means driven by said shaft to reciprocate said carriage back and forth and also oscillate said rolls in opposite directions back and forth during reciprocation of the carriage, mechanism mounted on said carriage for movement therewith for feeding the work bar forwardly relative to the carriage near the end of each forward stroke of the latter, said mechanism including a slide mounted on said carriage and advanced continuously relative to the carriage during operation of the rolls on successive longitudinal sections of the work bar, said mechanism also including a member mounted on said slide and rotatable continuously during advance of the slide, and a rotary drive connection extending to said rotary member and having rotary parts disengageable from each other to permit return of said slide without rotation of said member, said parts being interengageable with each other in one angular position only.
